SHOE ORNAMENT

Etienne Aigner, New York, N.Y., assignor to The Villager, Inc., Philadelphia, Pa., a corporation of Delaware

Filed Sept. 27, 1967, Ser. No. 8,763

Term of patent 14 years

U.S. Cl. D2—315
Int. Cl. D2—04

FIG. 1

FIG. 2

FIG. 3

FIG. 1 is a front elevational view of a shoe ornament showing my new design;

FIG. 2 is a sectional view taken on the line 2—2 of FIG. 1;

FIG. 3 is a top plan view thereof.

I claim:

The ornamental design for a shoe ornament, substantially as shown.
